UNITED STATES PATENT OFFICE.

DAVID A. TRIPP, OF BARBERTON, OHIO.

CABLE-SUPPORT.

1,296,571.

Specification of Letters Patent.

Patented Mar. 4, 1919.

Application filed September 6, 1918. Serial No. 252,926.

To all whom it may concern:

Be it known that I, DAVID A. TRIPP, a citizen of the United States, residing at Barberton, in the county of Summit and State 5 of Ohio, have invented new and useful Improvements in Cable-Supports, of which the following is a specification.

This invention relates to cable supports and it consists in the novel features herein- 10 after described and claimed.

An object of the invention is to provide a simple and durable support adapted to be used for sustaining an overhead or telpherage cable in a manner to permit the same 15 being extended in a zigzag line and at the same time to permit a carrier to pass freely along the same.

With this object in view the support comprises a bracket which may be mounted upon 20 posts or connected with overhead sustaining means and disks are journaled upon the said bracket and have at their periphery intermeshing teeth. The said disks are positioned from each other to such an extent that 25 the teeth of one disk do not completely fill the spaces between the teeth of the adjacent disk at the point where the said teeth intermesh.

A carrier is arranged to move along the 30 cable and the cable is supported upon the teeth of the disk at the point where they intermesh. The carrier includes a trolley wheel which is arranged to travel along the cable and which is journaled to a head. Vertically disposed spaced bars are attached to 35 the head and are adapted to move through the spaces between the teeth of the disk as the carrier moves between the disk. Additional wheels may be journaled at the head 40 of the carrier and these last mentioned wheels travel over lugs provided at the bracket and they may sustain the weight of the carrier at the time that the trolley wheel is passing over the intermeshing teeth and hence the cable and teeth will be relieved of 45 the load or weight of the carrier at the time that it is passing by the disks.

In the accompanying drawing:—

Figure 1 is a view in front elevation of 50 the cable support constructed in accordance with my invention.

Fig. 2 is a plan view showing the arrangement of the disk and the cable.

Fig. 3 is a side elevation of the carrier.

Fig. 4 is a bottom plan view of the same.

Fig. 5 is a view in elevation showing a

modified construction of bracket for supporting the disks.

Fig. 6 is a similar view of a further modification of the bracket for supporting the 60 disks.

The cable support comprises a bracket 1 which is preferably made of metal and which may be supported upon posts or from overhead appliances as desired or as occasion may 65 require. Disks 2 are journaled at the lower portion of the bracket 1 and lie approximately in the same horizontal plane. The said disks are provided at their peripheries with teeth 3 which intermesh with each 70 other. The disks 2 are spaced from each other for a distance sufficient to prevent the teeth of one disk from completely filling the spaces between the teeth of the other disk 75 at the point where the teeth of the disks intermesh. The upper surfaces of the disks 2 above the teeth 3 are curved or concaved as at 4 and these surfaces are adapted to bear against the cables hereinafter described.

The bracket 1 is provided at points above 80 the inner portions of the disks 2 with lugs 5. The intermediate portion of a cable 6 lies upon the teeth 3 at the point where they intermesh and is received within the curved or concaved portions 4 of the said disks. 85 The carrier which is adapted to move along the cable 6 comprises a head 7 to which is journaled a trolley wheel 8 and the said wheel is arranged to travel along the cable 6. Spaced parallel rods 9 are connected with 90 the head 7 and are adapted to move through the spaces between the teeth 3 of the disks 2 at the points where the teeth of both disks intermesh. Rollers 10 are journaled at the opposite sides of the wheel 8 and the head 7 95 and are adapted to move over and in contact with the lugs 5 as the rods 9 pass between the disks 2.

From the foregoing description taken in conjunction with the accompanying drawing 100 it will be seen that a cable support of simple and durable structure is provided and that a number of the said supports may be arranged whereby the cable may be stretched or led in an angular or zig-zag line. As the 105 rods 9 pass between the disks 2 the said disks are turned and the teeth 3 which were previously under the cable 6 are moved from under the same and other teeth are moved thereunder. At the same time the rollers 10 110 may move over the lugs 5 and in contact with the same and hence the disks 2 and the

teeth 3 are relieved of the weight of the carrier and its attachment as the rods 9 move between the disks 2.

Having described the invention what is claimed is:—

1. A cable support comprising a bracket, disks journaled thereon and having intermeshing teeth, a cable supported upon the teeth at the point where they intermesh, a carrier having a trolley wheel adapted to move along the cable and provided with a rod adapted to enter the spaces between the teeth at the points where the teeth of the disk intermesh, and means operating to relieve said cable and the disk of the weight of said carrier when the carrier passes the disk.
2. A cable support comprising a bracket having inwardly disposed lugs, disks journaled to the bracket and having intermeshing teeth, a cable supported upon the teeth

at the points where they intermesh, a carrier arranged to move along the cable and having a trolley wheel bearing upon the same, said carrier having a rod adapted to enter the spaces between the teeth at the points where the teeth intermesh and rollers carried by the carrier and adapted to move over the lugs and in contact with the same. 25

3. A cable support comprising a bracket, disks journaled thereon and having intermeshing teeth, the disks being concaved at their portions above the teeth, a cable supported upon the teeth and lying in the concaved portion, the carrier arranged to move along the cable and having a trolley wheel adapted to travel upon the cable, said carrier also having rods adapted to move through the spaces between the teeth at the points where the said teeth intermesh. 30

In testimony whereof I affix my signature. 40

DAVID A. TRIPP.
